FLUID SEALING AND BURR ELIMINATION
PROJECTILE FOR PERFORATOR GUNS

Pierre Dubost, Houston, Tex., assignor to Schlumberger Well Surveying Corporation, Houston, Tex., a corporation of Delaware

Application October 7, 1949, Serial No. 120,084

2 Claims. (Cl. 102—93)

1

The present invention relates to gun-type apparatus for perforating the metallic casings usually inserted in bore holes drilled into the earth, and more particularly to a new and improved form of projectile which is simple in construction and highly effective in operation.

Gun perforating apparatus employed heretofore for perforating well casings has usually comprised an elongated gun body adapted to be lowered into a bore hole and having lateral bores formed therein adapted to receive casing perforating projectiles. The projectiles were usually formed with a cylindrical body and a sharply pointed nose and stoppers were inserted in the gun bores ahead of the projectiles in an effort to seal the powder chamber behind the projectile from the bore hole fluid. Sometimes soft metal plugs were placed in the bore between the nose of the projectile and the stopper to prevent the formation of burrs in the casing when pierced by the projectile.

Apparatus of the type outlined briefly above has not been found to be entirely satisfactory. For one thing, a large amount of rubber was used in the stoppers in an effort to insure maximum effectiveness, so that an excessive amount of trash remained in the bore hole after the projectile was fired. Further, it was found that even large stoppers permitted some leakage of the bore hole fluid into the powder chamber under the high pressures and temperatures encountered in deep wells, particularly where the gun bore had become eroded from constant use. In addition, it was found that the soft metal plugs caused considerable damage to the gun bore and decreased the penetrating power of the projectile. Moreover, three time consuming operations were required to place a projectile, a burr eliminating plug and a stopper in each gun bore.

In an effort to overcome certain of the above-noted disadvantages, it has been proposed to employ a projectile of smaller diameter than the gun bore having its rear end mounted in a cup shaped element of soft metal and of the same diameter as the gun bore. It was found, however, that the cup shaped element tended to damage the gun bore just as the soft metal plugs did. Further, there was some likelihood that the soft metal cup shaped element would plug the perforation made by the projectile.

It is an object of the present invention, accordingly, to provide a new and improved projectile for gun perforators and the like which combines stopper and burr elimination features yet may be loaded as a unit in a gun bore in a single loading operation.

2

Another object of the invention is to provide a new and improved projectile for gun perforators and the like which includes means for eliminating burrs formed in a perforating operation, in a highly effective manner without damaging the gun bore or impairing the effectiveness of the perforating operation.

Still another object of the invention is to provide a new and improved gun perforating projectile of the above character in which the burr eliminating means serves both to center the projectile in the bore and to increase the depth of penetration thereof.

Yet another object of the invention is to provide new and improved gun perforating apparatus having stopper means for sealing a powder chamber in the gun from the bore hole fluid, which is highly effective under extreme pressures and temperatures, even when the gun bore is eroded.

According to the invention, a composite projectile is provided which comprises a casing piercing member of lesser diameter than the gun bore which carries a burr elimination member of substantially the same diameter as the gun bore at the rear end thereof, together with a bore stopper member located ahead of the burr elimination member. The burr elimination member surrounds the rear end of the casing piercing member and is made of hard metal so that it will flatten the burrs formed during the perforating operation upon impact therewith. It is designed to shatter upon impact with the casing, forming small pieces which drop harmlessly to the bottom of the bore hole and it may be suitably weakened to insure this result, if desired.

The bore stopper member, which is made of flexible material such as rubber, for example, surrounds the casing piercing member and is tightly fitted into the space between the latter and the interior wall of the gun bore. In one embodiment, it is provided with a flanged forward portion which is adapted to be forced more tightly into engagement with the interior wall of the gun bore as the pressure of the bore hole fluid increases, thereby effectively sealing the gun bore from the bore hole liquid.

According to another embodiment, a soft metal ring is fitted at the rear of the stopper member which is adapted to be forced more tightly into engagement with the wall of the gun bore as the pressure of the bore hole fluid increases. It thus prevents the stopper member from flowing around the burr elimination member in an eroded gun bore so that the bore seal is effectively maintained.

Additional objects and advantages of the invention will be apparent from the following detailed description of several typical embodiments, taken in conjunction with the accompanying drawings, in which:

Fig. 1 is a schematic diagram, partly in longitudinal section, of a composite gun perforating projectile constructed according to the invention;

Fig. 2 illustrates schematically a projectile of the type shown in Fig. 1 in position in a gun bore of a perforating gun; and

Fig. 3 is a schematic diagram, partly in longitudinal section, of another embodiment of the invention which is particularly useful in eroded gun bores.

In the form of the invention shown in Fig. 1, the composite projectile comprises a casing piercing member 10 including a rear cylindrical portion 11 of lesser diameter than the gun bore and a sharply pointed nose portion 12. Surrounding the rear portion 11 of the casing piercing member 10 is a substantially cylindrical sleeve 13 of substantially the same diameter as the gun bore, having an interior shouldered portion 14 on which the rear end of the casing piercing member 10 is adapted to be seated.

The sleeve 13 constitutes a burr elimination member and it is made of sufficient thickness and of a suitably hard metal to flatten the burrs surrounding a casing perforation upon impact therewith. The material comprising the sleeve 13 should also be brittle so that the sleeve 13 will shatter into small pieces upon impact with the casing. Materials having suitable hardness and brittleness for this purpose may include cast iron and certain brittle steels, for example. If desired, the sleeve 13 may be suitably weakened as by forming circumferential grooves 15 therein to facilitate its destruction upon impact.

Mounted on the casing piercing member 10 is a tubular stopper member 16 made of flexible material such as rubber, for example. Preferably, the stopper member 16 is bonded both to the casing piercing member 10 and to the forward edge of the burr elimination member 13. The stopper member 16 is provided with a forwardly and outwardly extending flange 17 which forms an effective bore seal as described below.

The loading of a gun perforator with composite projectiles of the type shown in Fig. 1 may be performed simply and quickly. All that is involved is the insertion of a composite projectile as a unit into a bore 18 of the gun 19, as shown in Fig. 2. Only one operation is required to load a gun bore, therefore.

In operation, the gun 19 is lowered into a well. As the pressure of the fluid in the well increases, the flange 17 on the stopper member 16 is forced more and more tightly into engagement with the inner wall of the gun bore 18, thus maintaining an effective seal between the powder chamber 20 and the bore hole fluid.

When the desired depth for perforation is reached, the powder charge 21 in the chamber 20 is ignited in any known manner and the composite projectile is fired from the gun 19, causing the casing piercing member 10 to perforate the well casing (not shown). Since the total cross sectional area of the casing piercing member 10 and the burr elimination member 13 is greater than the cross sectional area of the former alone, it will be understood that a greater force will be applied to the composite projectile than would be applied to the casing piercing member 10 alone. Hence, the composite projectile will have better

penetrating power than the casing piercing member 10 without the member 13.

The sleeve 13 forces the stopper member 16 against the well casing (not shown) causing it to disintegrate and fall harmlessly to the bottom of the well. The sleeve 13 is then driven against the burrs surrounding the perforation in the casing (not shown), thereby flattening them. The force of the impact shatters the brittle sleeve 13 into many small pieces which fall harmlessly to the bottom of the well.

As shown in Fig. 2, the burr elimination member 13 centers the casing piercing member 10 in the bore 18 prior to detonation of the explosive charge 21. Also, since the burr elimination member 13 has a relatively large area exposed to the forces developed by the explosion, it will not only remain attached to the casing piercing member 10 until the casing is reached but will increase the penetrating power of the member 10. Further, the burr elimination member 13, which is of substantially the same diameter as the gun bore 18, will not appreciably damage the latter since it is made of hard material.

If erosion of the gun bore 18 has taken place as a result of constant use, it will be understood that the burr elimination member 13 will not fit so tightly therein as before. In such case, it has been found that the stopper member 16 may flow around the burr elimination member 13 under extreme bore hole pressures and temperatures and may finally become sheared. If this occurs, the bore hole fluid may leak into the explosive chamber 20. This can be avoided by using a composite projectile of the type shown in Fig. 3.

In Fig. 3, the casing piercing member 10 and the burr eliminating member 13 are the same as in Fig. 1. However, the stopper member 16 is not flanged at its forward end but is provided with a metal ring 22 at its rear end made of soft metal such as annealed copper, for example. The ring 22 has an inwardly extending flange 23 lying between the members 13 and 16. With this construction, the hydrostatic pressure of the bore hole fluid acting against the stopper member 16 forces the ring 22 tightly against the eroded gun bore 18, thus preventing the stopper member 16 from flowing around the member 13. Preferably, the stopper member 16 is bonded both to the ring 22 and to the member 13. Thus, the composite projectile may be inserted as a unit into the gun bore 18.

The invention thus provides a novel and highly effective composite projectile which can be assembled quickly and easily in a bore of a gun perforator. By virtue of the construction described above, an effective seal is maintained between the gun bore and the bore hole fluid and burrs formed during perforating operations are eliminated. Moreover, these desirable features may be secured without damaging the gun bore or impairing the effectiveness of the perforating operation.

The specific embodiments disclosed herein are merely illustrative and are not to be regarded as imposing any restrictions whatsoever upon the scope of the following claims.

I claim:

1. A casing perforating projectile comprising a central casing piercing member including a substantially cylindrical body and a pointed nose, a first hollow sleeve member of hard, brittle metal mounted on said body and having weakening depressions formed therein, said first sleeve member having an inner shouldered portion against

which the rear end of said body is adapted to be seated, a second flexible sleeve member tightly fitted on said body ahead of said first sleeve member and a ring of soft metal around the rear portion of said second sleeve member and having a flange thereon extending between said first and second sleeve members.

2. A casing perforating projectile as set forth in claim 1, said ring of soft metal being bonded to the second sleeve member, and said second sleeve member being bonded to the first sleeve member, thereby to form a composite projectile assembly. 10

PIERRE DUBOST.
